United States Patent Office.

LEONARD FELKER, OF TEWKSBURY, MASSACHUSETTS.

Letters Patent No. 71,864, dated December 10, 1867.

IMPROVED CORN-CAKE CUTTER.

The Schedule referred to in these Letters Patent and making part of the same.

TO ALL WHOM IT MAY CONCERN:

Be it known that I, LEONARD FELKER, of Tewksbury, in the county of Middlesex, and State of Massachusetts, have invented new and useful Improvements in Corn-Cake Machines; and I do hereby declare that the following is a full and exact description thereof, reference being had to the accompanying drawings, and to the letters of reference marked thereon.

The nature of my invention consists in providing a corn-cake machine, having its several parts and devices so arranged and combined as to form, press, cut, and finish the cake at one operation, entire. To enable others skilled in the art to make and use my invention, I will proceed to describe its construction and operation.

Figure 1 represents a side elevation of my improved corn-cake machine.

Figure 2 represents a plan of the same.

Figure 3 represents a longitudinal section of the same.

Similar letters in the different figures indicate corresponding parts.
a represents the frame, the top of which is provided with suitable guides, *b b b*, on which the table *b'* slides. To this table *b'* are attached the racks *c c*. *d d* are two upright movable or adjustable stands, which are held in position by suitable screws, passing through the slots *e e* into the frame *a* permanently. Connected with and running in the adjustable stands *d d* is the pressure rotating cutting-cylinder *f*, this cylinder being provided with stationary cross-cutting knives *f' f'* and adjustable finishers *g g*, these finishers being operated by suitable springs, *g' g'*. The cylinder *f* is also provided with gears, *h h*, which are firmly secured on each end to the same, and connect with and gear into the racks *c c*. *i* is the rotating cylinder, which is provided with the required number of cutters, *i' i'*, running on its journals in the bearings of the adjustable stands *d d*. Attached and fastened to the cylinder *i* is the gear *j*. *j'* is the driving-shaft, which runs on its journals in the bearings of the adjustable stands *d d*, and is provided with a pulley or crank, *k*, to which the power is applied, and gear *l*, which connects with the gears *h* and *j*. *m* is the stationary cutter-cleaner, its object being to keep the cutters *i' i'* clean when in operation, and is secured by its arms to the cap *n*, which holds and connects the adjustable stands *d d* at the top. *o* is the weight, which is attached to the under side of the table *b'* by a cord, strap, or chain, which passes over a suitable pulley, indicated by dotted lines in figs. 1 and 3, and *p* is the lever, which is attached to the girt *q*, this girt connecting and fastened to the adjustable stands *d d*, the object of the lever *p* being to raise the adjustable stands *d d*, disengaging the gears *h h* from the racks *c c*; which allows the table *b'* to run back, by aid of the weight *o*, to its required location.

The machine being thus arranged and constructed, the power is applied to the crank or pulley *k*. The corn-cake material is suitably spread on the table *b'*. The operator then disconnects the lever *p* from the catch *r*, which allows the adjustable stands *d d* to descend, carrying down the cylinders *f* and *i*, which connects the gears *h h* with the racks *c c*, at the same instant bringing in contact the stationary knives *f' f'* and finishers *g g* with the cake-material, carrying forward the table *b'*, with its contents, directly in under the cylinder *i*, and in contact with the cutters *i' i'*, to the end of the racks *c c*. This operation completely presses, cuts the cake lengthwise and crosswise, entirely finishing it. The cake is then removed from the table *b'*. The operator then presses down the lever *p* into the catch *r*. This disengages and raises the entire apparatus from the table *b'*, allowing the table *b'* to resume its former position, by aid of the weight *o*, for another fresh lot of material. If more weight is desired to give the required pressure to the cake to finish the same, it can be applied to the stands *d d*, cylinder *f*, or girt *q*.

Having thus explained my invention, what I claim, and desire to secure by Letters Patent, is—

1. I claim the rotating cylinder *i*, with its cutters *i' i'*, in combination with the rotating cylinder *f*, with its stationary knives *f' f'*, and adjustable finishers *g g*, when arranged to operate for the purposes substantially as described and set forth.
2. I claim the pressure rotating-cylinder *f*, with stationary knives *f' f'*, and adjustable finishers *g g*, substantially as described and set forth.
3. I claim the cleaner *m*, in combination with the rotating cutters *i' i'*, as described.
4. I claim the adjustable stands *d d* and lever *p*, in combination with the table *b'* and weight *o*, when arranged to operate substantially as described.

LEONARD FELKER.
